UNITED STATES PATENT OFFICE.

ROBERT HUTTON, OF HOLYOKE, MASSACHUSETTS.

ADJUSTABLE DANDY-ROLL STAND.

SPECIFICATION forming part of Letters Patent No. 255,867, dated April 4, 1882.

Application filed February 20, 1882. (No model.)

To all whom it may concern:

Be it known that I, ROBERT HUTTON, of Holyoke, in the county of Hampden, Commonwealth of Massachusetts, have invented a new and useful Improvement in Adjustable Dandy-Roll Stands, of which the following is a specification, reference being had to the accompanying drawings.

Figure 1 is a front view of my invention, in which A shows the screw which moves the axle-support E vertically in a metal tube, D, which is attached to the support F F, which will be fastened to the machine-frame by means of screw C. The screw B B effects the horizontal adjustment of the apparatus.

Fig. 2 shows a cross-section of the above-named invention, more especially the screw A A and the support E. Screw A A is partly cut coarse where it runs through the cover G of tube D D. The lower part of the screw A A, moving support E, is fine cut, in order

to effect a slower movement of said support E, thereby making it absolutely adjustable. C in said figure shows a section of the screw which fastens said apparatus to the machine-frame, and by so fastening it makes it stationary.

Fig. 3 shows a section of support F F. The screw B B effects the horizontal movement of the entire apparatus except the screw C, which, as aforesaid, is made stationary by fastening to the frame.

I claim as my invention—

The combination of the coarse and fine cut screw by which the perfect adjustable movement of the support E is effected, and thereby the absolutely required position of the dandy-roll is secured.

ROBERT HUTTON.
